UNITED STATES PATENT OFFICE.

DAVID GOLDSMITH, OF NEW YORK, N. Y.

TRUNK OR HAT-BOX.

SPECIFICATION forming part of Letters Patent No. 601,073, dated March 22, 1898.

Application filed June 10, 1897. Serial No. 640,268. (No model.)

To all whom it may concern:

Be it known that I, DAVID GOLDSMITH, a citizen of the United States, residing at New York, in the county and State of New York, 5 have invented certain new and useful Improvements in Trunks or Hat-Boxes, of which the following is a full, clear, and exact description.

My invention relates to improvements in trunks and hat-boxes, and among the principal objects of the same are the following: the provision of a simple, inexpensive, and effective device, in combination with a trunk or hat-box, for permitting a hat to be readily secured in such a position as to prevent its being jostled about and injured during transportation, the said device being particularly useful in supporting and carrying ladies' hats, for which use the same is chiefly intended; further, providing a means whereby the said hat support and retainer may be readily detached, so as to permit the free use of the trunk or hat-box for other purposes.

My invention is illustrated by the accompanying drawings, in which—

Figure 1 is a plan view of a trunk-tray containing my invention. Fig. 2 is a vertical section of Fig. 1 on the line $x-x$. Fig. 3 is a vertical section on the line $y-y$, Fig. 1, illustrating details of construction.

A is a trunk-tray divided by suitable partitions. In one corner of said trunk-tray is a space chiefly intended to carry one or more hats. Practice has demonstrated that it is undesirable to loosely pack hats in trays or boxes for transportation, as the same are frequently jostled about to such an extent that the hat is injured. To obviate this danger, I provide a frame of substantially semi-ovoid shape secured at a suitable place in the tray A, over which frame the hat may be placed. B designates the said frame, the same being preferably formed of woven stiff material, such as light wire. The mesh of the said frame B is sufficiently open to allow free ventilation and to also allow a pin D to be passed therethrough, by which means the hat (illustrated by dotted lines) may be securely retained in position.

To permit the frame B to be removed so 50 that the trunk-tray or hat-box may be used for other purposes, I provide clips E E, secured at suitable points in the said tray or box, so that lugs F F, carried by the body B on substantially opposite sides, may be slipped 55 into place under said clips or retracted therefrom when it is desired to detach said frame. To prevent the accidental detachment of the said frame, I provide around its lower edge a suitable spring-reinforce G of slightly 60 greater diameter than the space between said clips E E, so that by attaching the lugs F F to the spring-reinforce at suitable points to register with said clips the expansive tendency of the said reinforce tends to hold the 65 parts securely in position.

While the accompanying illustration shows my invention as applied to the tray of a trunk and also shows only one frame secured thereto, it is manifest that the same is equally applicable to a box solely used for carrying hats, and one or more frames may be attached thereto at suitable points in the bottom, sides, or top thereof.

It is not my intention to limit myself as to 75 the material used or shape of the hat-retaining frame so long as the same will accomplish the ends herein mentioned.

Other means than the clips E may be used to secure the frame B in place in the trunk 80 or hat-box.

What I claim is—

1. In a trunk-tray or hat-box, a frame for securing hats, said frame having a central woven body of substantially semi-ovoid shape, 85 the mesh of same being sufficiently open to permit free ventilation and to also permit the passage of a retaining-pin, and a reinforce around the lower edge of said body, and retaining-lugs.

2. In a trunk-tray or hat-box, a frame for securing hats, said frame having a central woven body of substantially semi-ovoid shape, the mesh of the same being sufficiently open to permit free ventilation and to also permit 95 the passage of a retaining-pin, and a reinforce around the lower edge of said body and retaining-lugs carried thereby.

3. In combination a trunk-tray or hat-box, retaining-clips carried thereby, a hat-supporting frame having a spring-reinforce around its lower edge, lugs carried by said reinforce and registering with said retaining-clips, substantially as and for the purpose described.

Signed at New York, in the county of New

York and State of New York, this 3d day of June, 1897.

DAVID GOLDSMITH.
